BRUCE A. BRISTOW, OF TORONTO, ONTARIO, CANADA.

GAME APPARATUS.

Application filed April 8, 1927, Serial No. 182,154, and in Canada April 9, 1926.

This invention relates to game apparatus of the type in which a plurality of indicating devices are mounted on a horizontal bar and adapted to be tripped by levers arranged to be actuated by a ball, marble or the like rolled along the surface on which the apparatus stands.

My object in the present invention is to devise an arrangement by means of which substantially the same results may be obtained as in a game of five-pin bowling, or, in other words, to cause the indicators to trip in the same manner as the pins would fall according to the way the ball strikes the pin or pins.

I attain my object by means of the constructions hereinafter described and illustrated in the accompanying drawings in which

Fig. 1 is a plan view of my improved game apparatus;

Fig. 2 a section on the line 2—2 in Fig. 3;

Fig. 3 a front view of the apparatus;

Fig. 4 a detail showing a modified arrangement for counterbalancing the indicators; and

Fig. 5 a detail illustrating the means for assisting the means for tripping the indicators simultaneously.

In the drawings like numerals of reference indicate corresponding parts in the different figures.

My device comprises a pair of posts 1 which support adjacent their upper end a cross bar 3. On this cross bar a plurality of indicators 4 are mounted. Also pivoted on this cross bar are pivoted levers 5 by means of which the indicators are tripped.

The upper ends of the levers are forked, and the indicators are positioned in the recesses thus formed and are weighted so that their rear parts rest on the lever when in set position. This weighting may take the form of metal inserts 24 as indicated in Fig. 1, or a chamber 25 may be formed in each indicator as shown in Fig. 4 in which a metal ball 26 may roll from end to end.

The levers are supported at the proper angle by means of a bar 9. The levers will, of course, be of sufficient length so that their lower ends will be struck by a ball passing beneath them.

It is desirable, however, that it be possible to knock down various combinations of the indicators and I attain this result by

means of the mechanism I will now describe. The three intermediate levers 5, it will be noted, are each formed in three sections, the outer sections of the central lever 5 being numbered 5^a and the outer sections of the two adjacent levers being numbered 5^b. The two sections 5^a are connected by means of arms 10 to a tripper member 11 which extends below all the indicators and is pivoted on the support 3.

The lever sections 5^b of the indicator at one side of the central indicator are connected by arms 12 to a tripper member 13, also pivoted on the support and which extends beneath the adjacent outer indicator.

Similarly the lever sections 5^b of the indicator at the other side of the central indicator are connected by arms 12 to a second tripper member 13 also pivoted on the support and which extends beneath the adjacent outer indicator.

It should be stated, however, that the main parts of the levers are free to move without the outer sections 5^a and 5^b, but the said outer sections are provided with straps 14 which lie in front of the main sections so that movement of these sections is also imparted to the main part of the lever. To avoid danger of damage to the outer sections 5^a and 5^b, I provide straps 27 secured to the main lever sections, which straps extend behind the outer sections 5^a and 5^b. It will thus be seen that upon one of the outer sections 5^a or 5^b being struck by a ball, said outer section immediately engages the straps 27 and the shock is thus also distributed to the main lever section.

The operation of the parts just described is as follows. The ball is rolled along the floor or other surface on which the apparatus stands. If the ball strikes the main or central part of any lever, the indicator above that lever only will be tripped. If the ball strikes either of the lever sections 5^a, the tripper member 11 will be rocked and all five indicators will be tripped. If the ball strikes either lever sections 5^b of one indicator, one tripper 13 will be rocked to actuate the two indicators at one end, while if the ball strikes a lever section 5^b of the indicator at the other end, the other tripper 13 will be rocked to actuate the two indicators at that end.

Assuming, that the main part of the central lever be struck and the indicator

tripped, it is desirable that the lever sections 5^a be raised out of the path of the ball. I therefore so balance the tripper 11 that the transferring of the central indicator from set 5 to tripped position is sufficient to allow the tripper to rise enough so that the lever sections 5^a are out of the way of the balls.

So too the trippers 13 are so balanced that the tripping of their indicators is sufficient 10 to raise them to lift the lever sections 5^b out of the path of the balls.

Preferably, however, the tripper 11 is provided with adjustable weights 15 and each tripper 13 with an adjustable weight 16 15 whereby the balance of the trippers may be conveniently adjusted.

The bottom of the recess in the main part of each lever 5 will be so arranged that when the indicator is tripped the bottom of the 20 recess will be engaged by the indicator and the lever raised a sufficient distance so that its lower end is out of the path of the balls, while, as stated above, the mere transferring of the indicators from "set" to "tripped" 25 position is sufficient to allow the trippers to rise and lift the lever sections 5^a and 5^b.

While under ordinary circumstances the ball will strike the lever sections 5^a with sufficient force to cause the tripper 13 to lift 30 all the indicators, I may if found desirable provide special means for assisting in the operation of this tripper. This special means comprises a lever 28 pivoted on the supporting bar 3. One end of this lever carries 35 a weight 17, while the other end of the lever extends down behind the bar 9 and then upwardly immediately over the cross bar of the tripper 11. The weight 17 normally lies in such a position that very little 40 movement will cause it to tip forwardly upon a lever section 5^a being struck and movement is thus imparted to the tripper 11 and through it to the lever 28, thus causing the weight 17 to fall forwardly, and the portion 45 16^a of the lever to rise so as to engage and actuate the tripper sufficient to ensure the proper tripping of all the indicators.

A movable bar 18 is provided below and in front of the indicators to support the latter when in tripped position. By actuating 50 this bar the indicators may be returned to set position.

The arms 10 and 12 and the levers 5 are so proportioned in length that the levers 55 may pass by the trippers 11 and 13 when rocked under the impact of a ball. There is therefore no danger of the trippers 11 and 13 being accidentally actuated through being struck by the levers 5.

As there is a danger that balls may strike 60 the forward part of the base 1 and be diverted against the levers, I provide the inclined platform 20 up which the balls must travel to strike the levers. This platform is of 65 lesser width than the distance between the

uprights of the frame so that a space is left at each side between the platform and the uprights, forming in effect gutters, the sides of the platform forming abutments which prevent the balls which run off the side of 70 the platform from returning and striking the levers.

The wall is movable relative to the uprights of the frame 3, a resilient member 21 being interposed to hold the parts in normal 75 position. A guard 7^a is placed in front of the rear part of the wall and is held in spaced position relative thereto by means of resilient bumpers 8^a.

To prevent the balls after striking the 80 wall or guard 7^a escaping, I provide the apron 29 which is pivoted on supports 22 secured to the wall. This apron normally lies in such a position, as indicated particularly in Fig. 2, that balls will lift it when 85 passing inwardly, but cannot lift it when returning.

For the purpose of anchoring the apparatus as a whole I preferably connect the inclined platform to the base of the 90 uprights, by means of metal strips 23. These strips are made of thin material so as not to interfere with balls passing along the gutters.

When my apparatus is used in large or 95 bowling alley size, the uprights 1 for the cross bar 3 will usually be permanently secured in place and the wall and guard and inclined platform may be omitted.

If desired suitable numbers, letters or the 100 like may be applied in any convenient manner to the indicators for identification purposes.

It will be evident that many changes in the details of construction may be made in 105 my apparatus without departing from the spirit of my invention.

What I claim is:

1. In game apparatus, the combination of a supporting bar; a plurality of indicators 110 independently pivoted on said bar whereby each may occupy a "set" position or a "tripped" position; depending levers also pivoted on said bar, said indicators when in "set" position each resting on a lever but adapted to be rocked to tripped position by said lever when the latter is rocked; means for tripping said levers independently of one another; and means for tripping said levers collectively. 115

2. In game apparatus, the combination of a supporting bar; a plurality of indicators independently pivoted on said bar whereby each may occupy a "set" position or a "tripped" position; depending levers also 125 pivoted on said bar, said indicators when in "set" position each resting on a lever but adapted to be rocked to tripped position by said lever when the latter is rocked; means for tripping said levers independently of 130

one another; and means for tripping said levers in groups.

3. In game apparatus, the combination of a supporting bar; a plurality of indicators independently pivoted on said bar whereby each may occupy a "set" position or a "tripped" position; depending levers also pivoted on said bar, said indicators when in "set" position each resting on a lever but adapted to be rocked to tripped position by said lever when the latter is rocked; means for tripping said levers independently of one another; means for tripping said levers in groups; and means for tripping all of said levers simultaneously.

4. In game apparatus, the combination of a support; a plurality of indicators independently pivoted on said support whereby each may occupy a "set" position or a "tripped" position; means for tripping said indicators independently of one another; and means for tripping said indicators collectively, said means for tripping said indicators collectively being adapted to move out of action when a particular one of said indicators is tripped independently.

5. In game apparatus, the combination of a support; a plurality of indicators independently pivoted on said support whereby each may occupy a "set" position or a "tripped" position; means for tripping said indicators independently of one another; and means for tripping said indicators in groups, said group tripping means being adapted to move out of action when a particular indicator in its group is tripped independently.

6. In game apparatus, the combination of a support; a plurality of indicators independently pivoted on said support whereby each may occupy a "set" position or a "stripped" position; means for tripping said indicators independently of one another; means for tripping said indicators in groups, said group tripping means being adapted to move out of action when a particular indicator in its group is tripped independently; and means for tripping all of said indicators simultaneously, said means for tripping said indicators collectively being adapted to move out of action when a particular one of said indicators is tripped independently.

7. In game apparatus, the combination of a support; a plurality of indicators pivoted on said support whereby each may occupy a set position or a tripped position; a plurality of depending levers also pivoted on said support, certain of said levers when in normal position being each adapted to support an indicator in set position, but adapted when rocked to move the indicator to tripped position; and means connected with another of said levers when the latter is ac-

tuated adapted to trip said indicators simultaneously.

8. In game apparatus, the combination of a support; a plurality of indicators pivoted on said support whereby each may occupy a set position or a tripped position; a plurality of depending levers also pivoted on said support, certain of said levers when in normal position being each adapted to support an indicator in set position, but adapted when rocked to move the indicator to tripped position; and means connected with others of said levers adapted to trip said indicators in groups.

9. In game apparatus, the combination of a support; a plurality of indicators pivoted on said support whereby each may occupy a set position or a tripped position; a plurality of depending levers also pivoted on said support, certain of said levers when in normal position being each adapted to support an indicator in set position, but adapted when rocked to move the indicator to tripped position; means connected with others of said levers adapted to trip said indicators in groups; and means connected with still another of said levers adapted to trip all of said indicators simultaneously.

10. In game apparatus, the combination of a support; a plurality of indicators pivoted on said support whereby each may occupy a set position or a tripped position; a plurality of depending levers also pivoted on said support, certain of said levers when in normal position being each adapted to support an indicator in set position, but adapted when rocked to move the indicator to tripped position; a tripper member pivoted on said support and extending below a plurality of said indicators, said tripper member being adapted to be actuated by another of said levers; and means adapted to come into action when the said tripper member has rocked a certain distance to continue the movement of said member a sufficient distance to ensure tripping of the indicators.

11. In game apparatus, the combination of a support; a plurality of indicators pivoted on said support whereby each may occupy a set position or a tripped position; a plurality of said levers also pivoted on said support and adapted to be actuated by a game piece, each of said levers when in normal position being adapted to support an indicator in "set" position, but adapted when rocked to move the indicator to "tripped" position, one of said levers being formed of three sections, the central section being of sufficient width to permit the game piece to pass between the outer sections; and means actuated by said outer sections for tripping a plurality of said indicators simultaneously.

12. In game apparatus, the combination of a support; a plurality of indicators pivoted on said support whereby each may occupy a set position or a tripped position; a plurality of said levers also pivoted on said support and adapted to be actuated by a game piece, each of said levers when in normal position being adapted to support an indicator in "set" position, but adapted 10 when rocked to move the indicator to "tripped" position, one of said levers being formed of three sections, the central section being of sufficient width to permit the game piece to pass between the outer sections; means actuated by said outer sections for tripping a plurality of said indicators simultaneously; and means for rocking the central lever section when the outer sections are rocked.
13. In game apparatus, the combination of a support; an indicator pivoted on said support whereby it may occupy a "set" position or a "tripped" position; a depending lever pivotally connected with said support, 25 said indicator when the lever is rocked being adapted to move from "set" to "tripped" position; a U-shaped wall connected with said support; and a pivoted apron extending between the legs of the U-shaped wall, said 30 apron being adapted to permit the passage of a ball beneath it in one direction, but to prevent the passage of the ball in the opposite direction.
14. In game apparatus, the combination of a support; an indicator pivoted on said support whereby it may occupy a "set" position or a "tripped" position; a depending lever pivotally connected with said support, 35 said indicator when the lever is rocked being adapted to move from "set" to "tripped" position; a U-shaped wall resiliently connected with said support; and a pivoted apron extending between the legs of the U-shaped wall, said apron being adapted to 40 permit the passage of a ball beneath it in one direction, but to prevent the passage of the ball in the opposite direction.
15. In game apparatus, the combination of a support; a plurality of indicators pivoted 45 on said support whereby each may occupy a "set" position or a "tripped" position; means for tripping said indicators independently of one another; means for tripping said indicators collectively and adapted to be actuated by a game piece; and auxiliary means 50 adapted to come into action when said collective tripping means has completed part of its movement to ensure the continued movement of the said collective tripping means necessary to trip the indicators.
16. In game apparatus, the combination of a support; a plurality of indicators pivoted on said support whereby each may occupy a "set" position or a "tripped" position;
- means for tripping said indicators independently of one another; means for tripping said indicators collectively and adapted to be actuated by a game piece; and auxiliary means adapted to move into action when said collective tripping means has completed part 60 of its movement to ensure the continued movement of the said collective tripping means necessary to trip the indicators, said auxiliary means comprising a bell crank lever having one arm adapted to engage the support to limit its movement in one direction and its other arm weighted, said weighted arm being normally positioned to retain the first mentioned arm against the support, said first mentioned arm having an extension thereon adapted to be actuated by the collective tripping means to rock said lever, whereby the falling of the weighted arm will cause the main part of the first mentioned arm to engage and continue the movement of the collective tripping means.
17. In game apparatus, the combination of a support; an indicator pivoted on said support whereby it may occupy a "set" position or a "tripped" position; a depending lever pivotally connected with said support, 95 said indicator when the lever is rocked being adapted to move from "set" to "tripped" position; and an inclined platform up which the balls may be rolled, the sides of said 100 platform forming abutments to prevent a ball rolling over its sides returning and striking the lever.
18. In game apparatus, the combination of a supporting bar; a plurality of indicators 105 independently pivoted on said bar whereby each may occupy a "set" position or a "tripped" position; depending levers also pivoted on said bar, said indicators when in "set" position each resting on a lever but 110 adapted to be rocked to tripped position by said lever when the latter is rocked; means for tripping said levers independently of one another; and common means for actuating said levers to return the indicators to 115 set position.
19. In game apparatus, the combination of a supporting bar; a plurality of indicators independently pivoted on said bar whereby each may occupy a "set" position or a "tripped" 120 position; depending levers also pivoted on said bar, said indicators when in "set" position each resting on a lever but adapted to be rocked to tripped position by said lever when the latter is rocked; means for tripping said levers independently of one another; means for tripping said levers collectively; and common means for actuating the levers to return said indicators to "set" position.

Signed at Toronto, Canada, this twenty- 125 fifth day of March 1927.

BRUCE A. BRISTOW.
